UNITED STATES PATENT OFFICE.

E. O. ROOD AND S. H. HACKETT, OF LODI, ILLINOIS.

IMPROVEMENT IN THILL-COUPINGS.

Specification forming part of Letters Patent No. **59,455**, dated November 6, 1866.

To all whom it may concern:

Be it known that we, E. O. ROOD and S. H. HACKETT, of Lodi, in the county of Kane and State of Illinois, have invented new and useful Improvements in Thill-Couplings; and we do hereby declare that the following is a full and exact description thereof, reference being had to the accompanying drawings, making part of this specification, in which—

Figure 1 represents the elevation of the end of the thill; Fig. 2, the bottom view of the same; Fig. 3, the elevation of the axle-tree iron; Fig. 4, the top view of the same, and Fig. 5 the elevation of the coupling.

Similar letters of reference in each of the several figures indicate corresponding parts.

The nature of our invention consists in a device for attaching thills to the axle-trees, so arranged that the connecting-pin of the thill, by means of a spring attached to it, is kept fast in the slot of an iron attached to the axle-tree, or it can be easily disengaged from said slot by simple pressure, as will be hereinafter described.

To enable others skilled in the art to make and use our invention, we will proceed to describe its construction and operation.

The thill-iron A, terminating in two thick disks, B B, forms a fork, and a pin, C, is set fast into and runs through said disks. A lever, D, being set upon the pin C, and having the same for its axis, can freely move around it. It has a shoulder, E, at its end and a spring, F, attached to its front part, said spring being bent around the upper part of the lever and having its other end, f, free.

The iron attached to the axle-tree consists of a plate, G, and two standards, H H. The plate has a slot in a shape of T, into which enters lever D and its spring, when coupling is effected. The standards have slots h h on their top for the purpose of receiving the ends of the pin C.

The back side, t, of the T-slot forms an inclined plane for the purpose of forcing, by means of spring F, the lever D into the narrowest part of the slot.

The operation of the coupling consists in the following: To connect the thill with the axle-tree, the disks B B are put between the standards of the iron of the axle-tree in such a manner as to have the ends of the pin C enter into the slots h h of the standards, and the lever D, with its spring F, enter into the T-slot of the plate G; then, by pressing said disks downward, the end of the spring F, sliding along the inclined plane t of the T-slot, will force the lever C above its shoulder into the narrow part of the slot, and thus effect the connection.

To disconnect the thill from the axle-tree, the shouldered end of the lever D is pressed back toward the spring so much as to force it out of the narrow part of the T-slot into the wide one, thus disengaging it from the slot, and thereby disconnecting the thill from the axle-tree.

The device may be made of any metal suitable for the purpose, is convenient in use, and exempt from friction and rattling.

What we claim as our invention, and desire to secure by Letters Patent, is—

The combination of the shouldered lever D and its spring F, attached to the thill, with the T-slot of the axle-tree iron, the whole constructed and operating substantially in the manner herein described and specified, and forming the thill-coupling.

E. O. ROOD.
S. H. HACKETT.
